Anthony Duran Richardson & William Hollen Stevens Design for
Six Plate "or Box" Stoves
No. 953.

Patented Oct. 13, 1857.

Dec 953

N. P. Richardson & Wm. W. Stevens, of Portland, Maine.
Letters Patent No. 953. Dated Oct. 13th 1857.

The schedule referred to in these Letters Patent & making part of the same.

To all whom it may concern:

Be it known, that we, Nathaniel Putnam Richardson of Portland, and William Wallace Stevens of Westbrook in the county of Cumberland, the State of Maine, Partners under the firm of N. P. Richardson & Co. have invented or produced a new and ornamental design for a "Six Plate" or "Box" Stove (which we term the "North Star") and we do hereby declare that the following is a full and exact description of the same, reference being had to the accompanying drawings & to the letters of reference thereon. Of the said drawings

Figur¹. denotes a perspective elevation.

Figur². represents the top of the stove.

Figur³. represents the bottom of the stove.

Figur⁴. represents the cover.

Figur⁶. is a vertical section of the stove taken through

88

Dec. 953

the line A. B. Fig. 7. is a transverse section of the stone taken through the line C. D.

Fig. 8. is a transverse section of the front taken through the line E. F. We would remark, that the use of rays radiating from a center, is not a new design in stones in general: but it has never been used before on a "Six Plate" or "Box" stone in the form of an arched panel, with the rays radiating from a center, ornament, similar to that in the accompanying drawings.

What we claim is the ornamental design of the stone as shown in the drawings.

In testimony whereof we have hereunto set our hands and seals this sixteenth day of September A.D. 1857.

Witnesse:
